UNITED STATES PATENT OFFICE.

FREDERICK W. BRUSH, OF WINTHROP, MASSACHUSETTS.

FLASH-LIGHT.

1,201,550.

Specification of Letters Patent. Patented Oct. 17, 1916.

Application filed September 22, 1915. Serial No. 52,004.

To all whom it may concern:

Be it known that I, FREDERICK W. BRUSH, a citizen of the United States, and resident of Winthrop, in the county of Suffolk and State of Massachusetts, have invented certain new and useful Improvements in Flash-Lights, of which the following is a specification.

This invention relates to appliances for the use of dentists in illuminating the interior of the human mouth.

The invention is embodied in a flash light including an ordinary dry battery as the illuminating means, the light being adapted to be inserted in the mouth with convenience to both the patient and the operator, and also adapted to support a mirror in the mouth in position to reflect the rays of the lamp and illuminate surfaces in the mouth which are inaccessible to direct rays, the mirror being adapted to reflect the illuminated surfaces to the eye of the operator.

The invention consists in the improvements which I will now proceed to describe and claim.

Of the accompanying drawings forming a part of this specification: Figure 1 represents a view partly in longitudinal section and partly in elevation of a dental flash light embodying my invention, provided with a reflector; Fig. 2 represents a side view of the battery, and one of its terminals disconnected therefrom; Fig. 3 represents a side view of the incandescent lamp; Fig. 4 represents a perspective view of the mirror-holding device; Fig. 5 represents a perspective view of the mirror.

The same reference characters indicate the same or similar parts in all the views.

In the drawings, 12 represents a tubular container of any suitable thin sheet metal, such as brass or copper. The inner end of the container is provided with a detachable head 13, and its outer end is provided with a reduced tubular extension 12^a of sufficiently small size for convenient insertion in the mouth of a patient. The outer end portion of the extension 12^a is provided with an annular concaved flange 12^b and an internally threaded portion forming a lamp socket for detachably engaging the plug 15 of an incandescent electric lamp, the bulb of which is shown at 16. The flange 12^b is concaved to accommodate the bulb of the

lamp, and also to prevent rays of light passing backwardly into the eyes of the operator. The lamp is provided with a terminal 17, preferably of zinc, electrically connected with the filament of the lamp and suitably insulated from the perimeter of the plug 15.

The body portion of the container 12 is formed to contain an externally cylindrical dry battery 18, the general construction of which is the same as employed in so-called flash lights. The periphery of the battery 18 is surfaced with insulating material 18^a, which insulates the battery from the container. The battery has a terminal 19 at its outer end, and a terminal extension 19^a which projects into the extension 12^a and is adapted to make electrical contact with the lamp terminal 17, the extension 19^a being in effect a rod forming an extended or elongated battery terminal, although preferably separable from the battery, as shown by Fig. 2. The extended terminal 19^a is insulated from the casing extension 12^a by a surfacing of insulating material 19^b.

The container is provided with means for closing and breaking the circuit through the lamp, said means, as here shown, comprising a screw-thread connection at 13^a between the head 13 and the casing, and a resilient contact spring 20 attached to the head and arranged to bear on a terminal 19^b at the inner end of the battery. Rotation of the head 13 in one direction causes the spring 20 to contact with the terminal 19^b and close the circuit. The circuit is broken by a rotation of the head in the opposite direction separating the spring 20 from the terminal 19^b.

It will be understood that one side of the circuit includes the metallic wall of the container and its extension. The closing of the circuit of course renders the lamp filament incandescent.

The container may be provided with a mirror 26, which is detachably engaged with the reduced extension 12^a and is adapted to illuminate various internal surfaces of a patient's mouth and to reflect to the eye of the operator surfaces illuminated by the lamp. Said mirror is provided with a shank 27 having an offset screw-threaded portion 28.

29 represents a socket piece having an internally threaded socket 30 adapted to re-

ceive the shank portion 28. The socket piece is provided with spring clips 31 adapted to embrace the reduced extension 12^a of the container and thus secure the socket piece 5 and mirror to the extension.

It will be seen that by turning the head 13 in one direction the circuit is closed and the lamp filament rendered incandescent, and that by turning the head in the opposite direction 10 the circuit is broken, rendering the lamp inoperative. The heat radiated from the lamp warms the mirror and prevents condensation of moisture from the patient's breath thereon.

15 The elongated terminal 19^a enables a battery of ordinary length to be employed, and while said terminal may be permanently secured to the battery as a fixed part thereof, it is preferably separable from the battery 20 and formed as a loose connecting rod extending from the ordinary battery terminal 19 to the lamp terminal 17, the battery being removable independently, leaving said rod in place in the casing.

25 It will be seen therefore that an ordinary battery having the usual terminals 19 and 19^b may be employed, said battery being readily obtainable as an article of manufacture.

30 While any suitable battery may be employed, I prefer the so-called ever ready tungsten battery, patented February 18, 1913.

The described flash light is useful for many dental purposes without the mirror, 35 and is also adapted for the use of surgeons either with or without the mirror, the light

being used to illuminate the interior of the mouth.

Having described my invention, I claim:

1. A flash-light comprising a tubular battery container having a reduced tubular extension at one end, the extremity of which is provided with an annular flange and an internal screw thread, an incandescent lamp having a plug portion engaging said screw 40 thread and having its bulb seated against said flange, a battery within said container and insulated therefrom, an insulated rod located within said tubular extension and electrically connecting said lamp and said 45 battery, and means for making and breaking the circuit of the lamp.

2. A flash-light comprising a tubular battery container having a reduced tubular extension at one end, the extremity of which 50 is provided with an annular flange, an incandescent lamp engaged with the outer end of said extension and having its bulb seated against said flange, a battery within said container and insulated therefrom, an insulated rod located within said tubular extension and electrically connecting said lamp and said 55 battery, means for making and breaking the circuit of the lamp, in combination with a socket piece having 60 spring clips adapted to embrace said tubular extension back of said flange, and a mirror attached to said socket piece and positioned in front of said lamp.

In testimony whereof I have affixed my 70 signature.

FREDERICK W. BRUSH.
